WASHING MACHINE.
APPLICATION FILED MAY 18, 1916.

Patented Feb. 27, 1917.

2 SHEETS—SHEET 2.

UNITED STATES PATENT OFFICE.

WILLIAM N. RETTINGER, OF BOURBON, INDIANA.

WASHING-MACHINE.

1,217,636.

Specification of Letters Patent. Patented Feb. 27, 1917.

Application filed May 18, 1916. Serial No. 98,367.

To all whom it may concern:

Be it known that I, WILLIAM N. RETTINGER, a citizen of the United States of America, residing at Bourbon, in the county of Marshall and State of Indiana, have invented certain new and useful Improvements in Washing-Machines, of which the following is a specification, reference being had therein to the accompanying drawing.

10 This invention relates to washing machines and has for its principal object the production of a simple and efficient mechanism which consists of a minimum number of parts, wherein access may be had to the 15 interior of the washing machine for the purpose of facilitating the placing of clothes within the machine or the removal of clothes therefrom.

Another object of this invention is the 20 production of a simple and efficient means formed upon the inner face of the washing machine for producing a scrubbing action as the rotating member is operated.

With these and other objects in view this 25 invention consists of certain novel combinations, constructions, and arrangements of parts as will be hereinafter fully described and claimed.

In the accompanying drawings:

30 Figure 1 is a side elevation of the washing machine with the top thereof thrown to an open position.

Fig. 2 is a top plan view of the washing machine.

35 Fig. 3 is a central vertical section through the washing machine.

Fig. 4 is a section taken on the line 4—4 of Fig. 3.

40 Fig. 5 is a section taken on the line 5—5 of Fig. 3.

Fig. 6 is a detail perspective view of one of the fingers carried by the rotating arm.

Fig. 7 is a top plan view of one corner of the washing machine, showing the cover 45 moved.

Fig. 8 is a section taken on the line 8—8 of Fig. 4.

Fig. 9 is a detail perspective view of the rotating arm.

50 Fig. 10 is a detail perspective of the sleeve through which the rotating shaft passes.

By referring to the accompanying drawings it will be seen that 1 designates the body or receptacle of the washing machine which 55 is substantially conical in shape, that is to

say, tapers toward the upper end thereof, and this body or receptacle 1 is supported upon a plurality of cross braces or supports 2 carried by the radiating legs 3. These legs 3 pass vertically up the sides of the 60 body 1, as shown clearly in Fig. 1, and a cover 4 is mounted upon the top of these legs 3 and also upon the body 1, as clearly illustrated in Figs. 1 and 3.

The cover 4 is substantially rectangular 65 in shape and is provided with a central opening 5, which central opening 5 is normally closed by means of a top or cover 6. The top or cover 6 is provided with a bearing block 7, in which bearing block 7 is placed 70 a bearing sleeve 8. An operating shaft 9 is journaled in the bearing sleeve 8 and is capable of having longitudinal sliding movement through this bearing sleeve 8. This shaft 9 carries an arm or head 10 at the 75 lower end thereof by being threaded into the socket member 11 mounted upon the upper face of the head or arm 10. This head or arm 10 is provided with a plurality of apertures 12 within which apertures 12 fit the reduced ends 13 of the fingers 14, these fingers 14 diverging from the center of the arm 10, as illustrated clearly in Fig. 3 of the drawings.

A crank arm 15 is carried by the upper 80 end of the shaft 9 for facilitating the manual rotation of the arm 10, as will be obvious.

As stated above, the cover 6 is carried by the top 4 of the washing machine, and is 90 hinged to the side thereof by means of the hinges 16, thereby allowing the cover 6 to be swung vertically to the position shown in Fig. 1, when so desired, and permit the clothes to be placed within or removed from 95 the body of the washing machine.

It should be understood that in view of the fact that the shaft 9 is slidable within the sleeve 8 the head 10 may be drawn into close engagement with the inner face of the 100 door or lid 6 in order to allow the same to be withdrawn and prevent the head 10 from injuring the cover 4. It, of course, should be understood that a suitable wringer may be supported in any suitable or desired manner upon the washing machine, and the cover 4 is provided with a trough shape or inclined rear wall 17 to cause the draining water from the wringer or from the clothes while 105 the same are being removed from the recep- 110

tacle to drain into the receptacle and thereby prevent the water from draining upon the floor or the feet of the operator.

By carefully considering Fig. 3 and also Fig. 4 of the drawings it will be seen that the inner face of the receptacle 1 is provided with a plurality of spaced vertical corrugated plates 18 which plates are secured to the sides of the receptacle in any suitable or desired manner. These corrugated plates 18 will constitute an efficient scrubbing or rubbing member upon which the clothes are adapted to be rubbed for the purpose of efficiently cleaning the same. The bottom of the receptacle 1 is provided with a plurality of substantially V-shaped bottom plates 19 which plates have their abutting ends turned upwardly for constituting ribs 20, as is illustrated clearly in Fig. 8, the abutting edges of the ribs being bent downwardly to constitute flanges 21, these flanges 21 being adapted to be sealed or soldered together for constituting an efficient connection and smooth rubbing joint upon the bottom face of the receptacle.

It should be understood that the corrugated plates 18 comprising a portion of the inner wall of the washing machine will constitute a support at each corner of the top 4 for producing a support or abutment against which the outer edge of the top 6 is adapted to rest when in a closed position.

What is claimed is:

A washing machine of the class described comprising a body, said body provided with a corrugated lining, the corrugations extending vertically in said lining, a bottom positioned within said body and formed of a plurality of interlocking and compactly arranged segments, each segment provided with an upwardly inclined rib at its outer edge and terminating in a depending lip extending longitudinally throughout its length for producing a blunt scrubbing rib at each side edge of each segment, and said blunt scrubbing rib radiating from the center of said body.

In testimony whereof I hereunto affix my signature.

WILLIAM N. RETTINGER.
